T. EWBANK.

Tinning Lead Pipe.

Patented May 16, 1832.

May 16, 1832

St. Thomas, Edinburgh Patent, and making part of the
same, containing a description in the name of the said Thomas Curtaunt, his
of his improvement in the mode of coating lead pipes with tin.

To all whom it may concern: be it known, that I, Thomas Curtaunt, of the city
of New York, have invented, or made of coating lead pipes with tin, in a more effi-
cient manner than has been heretofore done, and by which the danger attending the
use of such pipes for the conveyance of water, and other liquids, is obviated, while
their cost is but little enhanced, and that the following is a full and exact description
of my said invention. I take the lead pipes, after they have been drawn to the required
size, and I coat them with tin, either on both sides, or on the inside only, as may be
required. To do this I prepare a batch of molten tin, in a vessel of a suitable form, the
which may vary according to the size of the pipe to be tinne'd. I regulate the heat of
this batch, so that the tin shall continue in a fluid state, without becoming sufficiently
heated to melt the lead. This may be ascertained ^{with} by the use of a thermometer, or by taking
it by a piece of lead, or by such a mixture of lead and tin as will fuse at a given tem-
perature: with a little experience, however, a workman will not find any difficulty
in accomplishing this object without such aids. When the pipe is to be tinne'd on
the inside only, I cover the outside with lampblack and resin, or with any other
article which will prevent the resin ^{from} getting upon it. I then blow powdered resin into
the pipe. When it is to be tinne'd on both sides, the resin is to be blown, or otherwise
placed, into the pipe, and the outside also is to be sprinkled with it, and it is then
got the fire. The molten tin should be kept covered with resin, fat, or other
suitable article, to prevent its agitation and to cool in the running. All that is ne-
cessary is then to pass the pipe through the molten tin, which when the pieces are
of considerable length, may be easily managed by hand, or when of considerable
length, and weight, a rope and pulley or any other suitable mechanical contrivance
which the workman may prefer may be resorted to. I am aware that the coat-
ing of lead pipes with tin, simply, is not new, the same having been heretofore
done, but in a manner less perfect than that which I have just described. The
lead has been tinne'd in sheets and afterwards made into pipes, or the pipes have
been made and tinne'd, and afterwards submitted to the intense fire. By neither of these
processes, however, is the interior security obtained with the same certainty with
any process of tinneing the pipes after they are drawn, glazed. The coating of

May 16, 1832

tin which undivided pipes, and these glasses are avoided which the former process can scarcely fail to produce. See out, therefore, claim as my invention the more turning of pipes made out of lead, but what I do claim is, the turning such pipes after they have been made to the purpose aforesaid hereinbefore set forth.
